UNITED STATES PATENT OFFICE.

NORBERT M. LA PORTE, OF BALTIMORE, MARYLAND.

PRESSURE-REGULATOR.

1,118,293.

Specification of Letters Patent. Patented Nov. 24, 1914.

Application filed August 17, 1914. Serial No. 857,076.

To all whom it may concern:

Be it known that I, NORBERT M. LA PORTE, a citizen of the United States of America, residing in the city of Baltimore, State of Maryland, have invented certain new and useful Improvements in Pressure-Regulators, of which the following is a specification.

This invention relates to a method of and apparatus for limiting the pressure in a steam boiler. At the present time the universally accepted means for accomplishing this kind of regulation is the pop safety valve. The safety valve, while perfectly reliable and unfailing in its effectiveness to accomplish the main object in view, that is, to prevent the increase of boiler pressure beyond the pre-determined point, has various inherent disadvantages. The loss of steam at maximum pressure due to the blowing of the safety valve is considerable. When figured in actual coal consumption and, in turn, in dollars and cents thus wasted, the loss amounts to an item of tens and even hundreds of thousands of dollars in the yearly expense of the larger railroads. The noise of the blowing safety valves on locomotives in thickly populated districts is a subject of frequent complaint and of legislation in several States. Further, the loss of steam pressure and heat in this way is an actual source of difficulty to the engine driver and fireman.

In the case of locomotives drawing fast trains it is customary to maintain the full working pressure in order that speed may be obtained and the fireman keeps the pressure up to the point where the safety valve feathers. It is almost impossible to avoid the generation of excess of steam under these conditions which causes the opening of the safety valve with the losses in heat units and steam pressure and wear upon the safety valve which invariably follow. This is especially true when steam is cut off from the cylinders when approaching stations and in city yards where the noise of the safety valve is especially objectionable.

To eliminate these various disadvantages and provide means for limiting the pressure in a steam boiler without blowing of the safety valve is the object of my invention. To this end I provide means under control of the boiler pressure to be actuated when that pressure rises in excess of the pre-determined working pressure whereby water

is automatically fed to the boiler to cool the contents and take up the excess heat, thereby retarding the generation of steam and avoiding the necessity for the frequent 60 operation of the safety valve, with the consequent loss of heat units.

As a means for feeding water to the boiler I may use any type of pump or supplementary injector or even the service injector of 65 the boiler connected to a pressure control for this purpose and while the device is capable of various applications, it is preferably used, particularly in locomotives in connection with and supplementary to the regular 70 safety valve, to prevent the frequent blowing of the safety valve and in its preferred form, the equipment consists of a supplementary injector connected to the boiler to be operated when the boiler pressure rises 75 above a predetermined normal, the steam pipe leading from the boiler at a point in the plane of the maximum water level so that the injector will be flooded and cannot operate when there is an excess of water in 80 the boiler. While this is an effective means for preventing the injection of an excess of water into the boiler, it will be clearly apparent that other means to this end may be adopted within the scope of my invention 85 which relates not only to the apparatus described and various equipment whereby the kind of regulation described may be accomplished but also to the method of limiting the pressure in a steam boiler which consists 90 in injecting water into the boiler whenever the pressure rises above a pre-determined normal and checking the injection of water whenever there is an excess of water in the 95 boiler.

In the drawings I have illustrated a portion of a locomotive boiler to which a device embodying my invention has been applied.

Figure 1 is an elevation of a portion of the boiler and cab showing the equipment. Fig. 100 2 is a detailed view partly in section illustrating the feeding device and operating mechanism.

Referring to the drawings by numerals each of which is used to indicate the same 105 or similar parts in the different figures: I have shown a locomotive boiler 1, a cab 2, a service injector 3, manually controlled to feed water to the boiler under ordinary circumstances and an auxiliary or supplemental injector 4, which is the pressure controlled, water feeding member referred to 110

herein. This injector 4, for which any other pressure controlled, feeding device may be substituted within the scope of my invention, is illustrated in Fig. 2. In the preferred form it is an ordinary, feed, water injector of small capacity, as compared to the service injector, taking steam from the boiler by way of the pipe 5, which leads from the boiler at the maximum desired water level within the boiler indicated by the dotted line 6, in Fig. 1. Water is supplied from the tender by way of the pipe 7, and the delivery is by way of the pipe 8, to the top of the boiler at 9.

The control referred to is accomplished by means of the injector throttle valve 10, moved by means of a sliding rod 11, which carries at its rear end a piston 12, working in a fluid pressure cylinder 13. A spring 14, tends to advance the piston 12, holding the valve 10, normally seated. In the controlling operation, the valve 10, is lifted from its seat when the pressure in the boiler rises above the pre-determined working pressure. This is accomplished by the introduction of fluid in front of the piston 12. To this end I provide a port 14', leading to the cylinder 13, in front of the piston. This port is controlled by a valve 15, actuated by means of a diaphragm 16, depressed by means of a spring 17, so that the valve 15, is normally seated. Fluid pressure acting contrary to the tension of the spring 17, tending to raise the diaphragm and unseat the valve 15, is supplied by means of a pipe 18. This pipe may lead either to the steam or water space of the boiler and in this instance it leads fluid under pressure to the port 14' of the cylinder 13, as well as to the lower side of the diaphragm 16. To permit the escape of steam and condensed water from the cylinder 13 when the valve 15, closes owing to a drop of pressure within the boiler, a needle valve or other suitable escape valve 19, is provided. This is open slightly permitting the steam to escape slowly so, that unless the supply through the inlet port 14' is maintained, the pressure in front of the piston 12, is relaxed permitting the spring 14, to seat the valve 10, but as long as the pressure in the boiler is maintained above the pre-determined working pressure, the supply of steam retained in the cylinder 13, in excess of what escapes through the valve 19, is sufficient to compress the spring 14, and hold the valve 10, in open position.

In order to give notice to the fireman of the fact that the pressure within the boiler is in excess of the working pressure so that he may regulate his firing accordingly, a pipe 20, is led from the cylinder 13, to a diaphragm 21, which, when there is pressure in the cylinder 13, serves to open a valve in the pipe 22, allowing compressed air to pass from the air reservoirs upon the engine to a whistle 25, or other signal located conveniently to the fireman's working position.

The operation of the device will be easily understood from the preamble and drawing taken in connection with the specification. The spring 17, is tensioned by the screw 17' to permit the opening of the valve 15, by the boiler pressure upon the diaphragm 16, when the pressure reaches a point about two pounds below the pressure at which the safety valve which may be and preferably is used in connection with this equipment, would blow, steam or water is admitted to the cylinder 13, the pressure thus transmitted acts upon the piston 12, opening the throttle 10, of the injector 4, causing the water to be fed into the boiler so that the excess of heat is taken up by the incoming feed water, reducing the temperature and retarding the generation of steam to such an extent that the pressure almost immediately drops below the point of regulation and the diaphragm 16, closes the valve 15, permitting the valve 10, of the injector 4, to close so that the automatic feed of water is discontinued. There are circumstances under which the maximum quantity of water is already in the boiler and it would be detrimental to add more. If this condition exists the water will flow through the pipe 5, and flood the injector preventing its feeding action, for it will be remembered that the pipe 5, enters the boiler at the high water level and it is easily apparent that the injector cannot operate merely with a supply of hot water, it must have steam to act on the feed water in order to be operative.

The method of my invention consists in regulating or limiting the pressure of a steam boiler by injecting water into the boiler whenever the pressure exceeds the pre-determined working pressure and discontinuing the injection of water whenever the water in the boiler exceeds the desired maximum level.

I have thus described my invention specifically and in detail in order that its nature and operation may be clearly understood, however, the specific terms herein are used in their descriptive rather than in their limiting sense and the scope of the invention is defined in the claims.

What I claim is:

1. In combination with a steam boiler for limiting the pressure in the boiler means for feeding water to the boiler and automatic means actuated by the variation of boiler pressure for controlling said feeding means to feed water to the boiler when the pressure rises above normal.
2. In combination with a steam boiler for limiting the pressure in the boiler, means for feeding water to the boiler and means actuated by the variation of boiler pressure for controlling said feeding means to feed

water to the boiler when the pressure rises above normal and means for discontinuing the operation of the feeding means whenever the water level in the boiler exceeds a pre-5 determined maximum.

3. In combination with a steam boiler for limiting the pressure in the boiler, a water feeding device, a throttle valve for said device, a fluid actuated member operatively 10 connected with said throttle valve for opening the same and a valve actuated by the boiler pressure when in excess of the normal working pressure of the boiler to operate said fluid actuated member to open the 15 throttle and operate said boiler feeding device.

4. The combination with a steam boiler of an automatic pressure-controlled boiler feeding device responsive to pressures in excess 20 of the normal working pressure of the boiler, whereby water will be automatically fed to the boiler during the maintenance of excess pressure therein.

5. The combination with a steam boiler 25 and the main feeding device therefor of an automatic auxiliary pressure controlled, feeding device responsive to pressures in excess of the normal working pressure of the boiler, whereby water will be automatically fed to the boiler during the maintenance of excess pressure therein.

6. The combination with a steam boiler of a pressure-controlled injector responsive to pressures in excess of the normal working 35 pressure of the boiler, whereby water will be automatically fed to the boiler during the maintenance of excess pressure therein.

7. The combination with a steam boiler 40 and main feeding device therefor of an auxiliary pressure-controlled injector responsive to pressures in excess of the normal working pressure of the boiler, whereby water will be automatically fed to the boiler during the maintenance of excess pressure 45 therein.

8. The combination with a steam boiler of a pressure-controlled boiler feeding device taking steam from the boiler at the desired 50 high water level thereof and responsive to pressures in excess of the normal working pressure of the boiler, whereby water will be automatically fed to the boiler during the maintenance of excess pressure and a water

level lower than the desired high water level thereof.

9. The combination with a steam boiler and main feeding device therefor of an auxiliary injector taking steam from the boiler at the desired high water level thereof and responsive to pressures in excess of the normal 60 working pressure of the boiler, whereby water will be automatically fed to the boiler during the maintenance of excess pressure and a water level lower than the desired high water level thereof.

10. The combination with a steam boiler of a boiler feeding device, a throttle valve for said device, a fluid actuated piston operatively connected with said valve to open the same, and a valve actuated by the boiler 70 pressure in excess of the normal working pressure of the boiler to admit fluid to said piston to open said throttle to automatically operate said boiler feeding device.

11. The combination with a steam boiler 75 of an injector connected to feed said boiler, a cylinder, a spring-return piston in said cylinder and operatively connected with the throttle of said injector to open and close the same, a valve for admitting fluid from 80 said boiler to said piston to actuate the same and open said throttle, a diaphragm operatively connected to said valve and exposed to the boiler pressure, a spring tensioned to normally hold said valve closed and yield 85 to permit said valve to open when the boiler pressure exerted on said diaphragm is in excess of the normal working pressure of the boiler.

12. The combination with a steam boiler 90 of a pressure-controlled boiler feeding device responsive to pressures in excess of the normal working pressure of the boiler, and a signal valve actuated simultaneously with the actuation of said boiler-feeding device, 95 whereby water will be automatically fed to the boiler and a signal actuated during the maintenance of excess pressure within the boiler.

Signed by me at Baltimore, Maryland, 100 this 15th day of August 1914.

NORBERT M. LA PORTE.
